CALKING RING

Application filed December 17, 1928. Serial No. 326,671.

This invention relates generally to means for closing mold cavities surrounding annular bodies and refers particularly to devices for use in the sealing of joints.

5 An object of the invention is to provide a device adapted to greatly facilitate the sealing operation. This device may broadly be considered a closure for mold cavities and in the specific form shown and described here-
10 in consists of a ring-shaped member which may be termed a calking ring and which is adapted to be sprung over one of the parts to be joined and to be moved into engagement with the other part and to form therewith
15 a mold for receiving the sealing material such as molten metal, this calking ring being adapted to be removed as soon as the metal has hardened and subsequently applied to other joints.

20 With these and other objects in view the invention consists in certain novel features of construction, combinations and arrangement of parts as will be more fully described and particularly pointed out in the appended claims.

25 In the drawings:

Figure 1 is a top plan view of a pair of pipe sections ready to be joined together and my calking ring applied thereto in operative position;

Figure 2 is a perspective view of the spring metal core.

Referring now to the drawings and particularly to Figure 1, the numerals 1 and 2 designate pipe sections which are to be joined together, the section 2 being provided at one end with the usual enlarged hub portion 3 within which is received the end portion of the section 1. This is the usual construction of such sections and the arrangement is such that an annular space or mold cavity is provided between the outer face of the section 1 and the inner face of the hub to permit a sealing material such as molten lead to be poured in the opening and hardened. The usual procedure is to clamp an asbestos or oakum rope around the annular opening to complete the mold for the molten metal or to close the annular opening with putty or clay, which also completes the mold. Both of these

methods are slow and inefficient, however, and to obviate this condition I have provided what may be termed a calking ring which is designated by the numeral 4. This ring as shown in the drawings, is of substantially 55 annular or ring-shaped formation and consists of a spring metal wire 5 having a covering 6 of non-combustible material such as asbestos within which the wire is imbedded. This construction gives to the calking ring a 60 sufficient springiness so that it may be easily attached to and removed from a pipe section by springing the ends of the ring apart.

In the present instance the asbestos covering is shown as being square in cross section 65 so that when the ring is slipped upon the section 1 and moved into engagement with the flat end of the hub, it will form a seal therewith. The ring, when applied to the pipe sections, closes the annular opening or space 70 and forms with the hub, a mold for receiving the molten metal.

In order to provide a pouring spout or opening, the ring is provided with a laterally offset portion 7 adjacent one end, a portion 8 projecting from the portion 7 and lying parallel to the main body of the ring, and an extreme end portion 9 directed inwardly and adapted to slidably engage the other end 10 of the ring. It will be apparent that different sized rings will be made for different sizes of pipes and for a particular size of pipe the ring adapted therefor is so designed that the end portions will lie substantially in the position shown in Figure 1 so that the 85 ring will form with the hub an opening 11 through which the molten metal may be easily and quickly poured and directed to the annular space between the sections.

It will be apparent that any slight inaccuracies in the size of a pipe section is compensated for by the arrangement of the end portions of the ring. Therefore if a pipe section is slightly larger or smaller, the overlapping portion 9 may slide relative to the end portion 10 to compensate for such inaccuracies. In order that a tight fit or joint may be formed between the end portions of the ring, it is formed so that these portions are urged together so that while the portion 100

9 may be moved relative to the end 10 there will always be a tight joint between these parts which will prevent any of the molten metal from escaping.

5 After the sealing material has been poured through the opening 11, it is permitted to harden sufficiently and the end portions of the ring are sprung apart to permit the removal of the ring from the section 1, whereupon it may be subsequently utilized in the 10 sealing of additional joints.

While I have specifically shown and described my calking ring as being applied to pipe sections, it will be apparent that this is 15 not the only use to which it may be subjected and that the same is equally efficient in babbitting bearings on shafting.

In fact the use of my ring is a decided improvement on the usual method of sealing the 20 joint with putty or clay and pouring the metal through the oil hole on top of the boxing. When a calking ring is used, the metal will be poured at the end of the boxing, permitting the air to escape through the oil hole 25 and thus provide a smoother bearing in which air pits are eliminated.

I wish it to be understood that I do not limit my calking ring to the uses mentioned above and that it may be utilized wherever 30 it is desired to provide a closure for mold cavities surrounding annular bodies.

What I claim as my invention is:

1. A closure for mold cavities surrounding annular bodies comprising a split ring-shaped member adapted to be sprung over the body and to close the cavity, said member being provided at one of its ends with a laterally offset portion that forms with the other end an opening through which the material 40 to be molded, may be poured.

2. A calking ring comprising a split ring of yieldable material having a laterally offset substantially U-shape portion, and a covering for said ring and offset portion, the 45 covering for a portion of the ring and for said offset portion forming a pouring spout.

3. A calking ring comprising a split metal ring having a laterally offset substantially U-shape portion at one end, and a covering 50 of asbestos for said split ring and offset portion, the covering for a portion of the ring overlapping and cooperating with the offset portion aforesaid to form a pouring spout.

4. A device of the class described comprising a transversely split ring-shaped member of yieldable material having a laterally offset substantially U-shaped portion opening toward and bridging the split, one side of the 55 U constituting an extension of said member at one side of the split, and the other side of the U being against but separable from the member at the other side of the split.

5. A device of the class described comprising a split ring-shaped member having oppo-

site ends thereof spaced apart, and having a substantially U-shaped portion bridging the gap between the spaced ends aforesaid, said U-shaped portion opening toward and cooperating with the space or gap between said ends to form a pouring spout. 70

6. A calking ring comprising a transversely split metal ring, and a cover of non-combustible material for said split ring having a substantially U-shaped laterally projecting 75 offset portion opening toward and forming with spaced portions of the covering on said ring a pouring spout.

7. A calking ring comprising a transversely split metal ring having a laterally projecting substantially U-shaped offset portion, and a covering for said ring and offset portion formed of non-combustible material, said covering throughout its length being substantially square-shape in cross section, 85 and the covering for the offset portion cooperating with the covering for the ring to form a pouring spout. 80

In testimony whereof I affix my signature.
